UNITED STATES PATENT OFFICE

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS

MULTIPLE-OPERATED STANCHION

Application filed June 26, 1926. Serial No. 118,700.

This invention relates to multiple-operated stanchions for use in cow stalls, and is fully described in the following specification and shown in the accompanying drawings, in which:

Figure 1 is a rear elevation of the stall front with stanchion mounted therein, showing the stanchion closed;

Fig. 2 is a similar view showing the stanchion open;

Fig. 3 is a top plan view of the stall front slightly enlarged;

Fig. 4 is an enlarged partial vertical longitudinal section on the line 4 of Fig. 3;

Fig. 5 is a similar transverse section on the line 5 of Fig. 3;

Fig. 6 is an end elevation of the right-hand end of the stall front;

Figs. 7, 8 and 9 are sections on the lines 7, 20 8 and 9 of Fig. 3;

Fig. 10 is an enlarged partial section on the line 10 of Fig. 3;

Fig. 11 is a partial top plan view of the same;

Fig. 12 is a partial vertical section on the line 12 of Fig. 10; and

Fig. 13 is a side elevation partly in section showing the bottom part of the stanchion.

The embodiment illustrated comprises a stall having a front made up of vertical pipes 10 and 11 which may be secured to a concrete curb 12 by any suitable means such as clamps 13. The top member of the stall front consists of two spaced facing U-shaped members 14 as shown in Fig. 5 which are secured to the tops of the pipes 10 and 11 by means of the spacer-clamps 15 and 16 and the bolt 17.

A stanchion A is hingedly suspended from its top by means of a swivel bolt 18 to a member 19 which is secured to the spaced top members 14 by means of a bolt 20 as shown in detail in Fig. 10. The lower part of this stanchion is loosely connected to the member 21 by means of a pin 22 and chain 23.

A head 24 is slidably mounted between the spaced top members 14 and carries two parallel slide rods 25 which are guided in the casting 26 at the top of the pipe 10. The head 24 carries a pin 24^a on which is pivotally mounted one end of the link 27, the other

end being pivotally mounted in the outer end of the crank 28 which is journalled on the upper end of the pipe 11 and retained in place by means of a set collar 29. An operating lever 30 is pivotally connected to the crank 28 by means of a pin 31 and has a slot 32 which is adapted to fit over either of the pins 29^a or 29^b on the two sides of the set collar 29. As shown in Fig. 1, the operating lever 30 covers the pin 29^a.

The parallel slide rods 25 carry a casting 33 which is adjustably secured thereon by means of set screws 34 and on this is carried a finger 35 which is pivotally connected by the pin 36. The free end of this finger is grooved upwardly and normally rests on top of the top members 14.

In Fig. 1 the spaced slide rods 25 are at the extreme right-hand end of their throw with the operating lever 30 locked over the pin 29^a while in Fig. 2 the rods 25 are at the extreme left of the throw with the lever 30 locked over the pin 29^b. In the latter position the finger 35 extends some distance beyond the extension 37 of the upper stanchion member 38 which lies between the top members 14 and which is secured to the movable stanchion member 39, the latter being pivotally mounted at 40 to the C-shaped stanchion frame 41. A spring 42 (see Fig. 13) tends to maintain the stanchion side bar in an open position as shown in Fig. 2. The stanchion side bar 39 is pivotally connected at 43 to a slotted guide member 44 which extends through the hollow top member 45 and surrounds the bolt 46. As shown in Fig. 2 the guide member is at the outermost end of its stroke and is stopped by the bolt 46. As previously stated the extension 37 does not quite engage the finger 35 in this position.

To close the stanchion from the position shown in Fig. 2, the lever 30 is raised until it clears the pin 29^b and this lever is then swung around through an angle of substantially 180° to the position shown in Fig. 1. During this operation the finger 35 picks up the extension 37 and brings it up to the closing position wherein this stanchion 37 is substantially on the same axial line as the 100

pin 18 so that in the closed position the stanchion A is free to swing about while in the open position shown in Fig. 2, it is held parallel to the stall front. A bar 47 is rigidly connected to the pipe 10 for preventing the cow from getting her head through the stall front at the left of the stanchion and a bar 48 is pivotally mounted at 49 to the pipe 11 at the right-hand side of the stanchion, the upper end passing through the space between the top members 14 and resting against the head 24. Gravity holds it in contact with this head so that it moves back and forth therewith.

It will be understood that the stall front and stanchion illustrated is only the right-hand one of a series which may consist of two or more and that the other are substantial duplications except for the matter of the operating lever 30 and the parts immediately related thereto. Top members 14^a are secured to the ends of the top members 14 by means of a filler member 14^b and a bolt 14^c. Likewise the slide rods 25^a are secured to the ends of the slide rods 25 by gripping members 25^b and bolts 25^c.

It will be understood from the foregoing that moving the slide rods 25 to the left moves all of the fingers 35 thereby permitting all of the stanchions to open simultaneously. Likewise moving the slide rods 25 to the right closes all of the stanchions.

If it is desired to open any of the stanchions while the others are closed, this may be done by raising the finger 35 for that particular stanchion. When the slide rods 25 are again moved to the open position, the fingers 35 which are concavely grooved on the lower surface, as shown in Fig. 10, and which have thus been raised to open one or more of the individual stanchions will pass over its extension 37 and because of said concave groove will be guided thereon and drop behind the extension 37 and on movement of this slide rod again to the right will close these stanchions as well as all of the others.

It is also sometimes desirable to retain one or more of the stanchions locked while opening the others, and for this purpose I have added a clip 50 which is journaled on one of the slide rods 25 and which has a shoulder 51 which engages a shoulder on the casting 52 so that while it is adapted to turn on the slide rod, it will not shift endwise thereon. This clip has an ear 53 which is adapted to be drawn over in front of the extension 37 and to rest upon the opposite slide rod as shown in Fig. 11. When this is done that particular stanchion will remain locked in closed position while the others not so locked will open when the operating lever is again moved to open position.

If desired, the link 27 (Figs. 1 and 3) may be moved and placed on the opposite

side of the post 11 in which case the operating lever 30 will then swing in the opposite direction from that which has been described.

A roller 24^b on the pin 24^a lies between the facing members 14 and serves to take the heavy lateral thrust of the link 37 when a great number of stanchions are set to be operated in series. This arrangement permits many more stanchions to be thus operated.

While I have shown and described but a single embodiment of this invention, it is to be understood that it is capable of many modifications. Changes therefore in the construction and arrangement may be made which do not depart from the spirit and scope of the invention as disclosed in the appended claims.

I claim:

1. In combination, a stall front having a top bar with a longitudinal slot therein, a plurality of stanchions pivotally hung beneath said bar each having a side bar pivotally mounted at its lower end, the upper end of the side bar having an extension passing through said slot, said extension being in axial alignment with the upper pivot of said stanchion, means for simultaneously opening and closing the side bars, and a latch member movable about a horizontal axis extending in the direction of the movement of said means and operating to retain one of said extensions in closed position while the remainder are opened by said opening and closing means.

2. In combination, a stall front having a top bar with a longitudinal slot therein, a plurality of stanchions pivotally hung beneath said bar, each having a side bar pivotally mounted at its lower end, the upper end of the side bar having an extension passing through said slot, said extension being in axial alignment with the upper pivot of said stanchion, a sliding member on said top bar, means thereon for operating said side bars, a lever for operating said sliding member, said lever being pivotally mounted on a vertical corner post of the stall, and having a link connecting it to said sliding member, said link being movable to either side of said post to permit the lever to be reversed.

3. In a stall front, a top bar having spaced longitudinal U-shaped members, spacers separating said members and having openings serving as guides, vertical posts, said spacers partially clampingly embracing said U-shaped members, bolts for securing said spacers to the posts, and rods slidable in said guides.

4. In a stall front, a top bar having spaced longitudinal members, spacers separating said members and having openings serving as guides, means for securing said members and spacers together, a stanchion pivotally hung beneath said bar and having a side-bar

5 pivotally mounted at its lower end, the upper end of the side-bar having an extension guided by said longitudinal members, a pair of horizontally spaced rods guided in the
10 spacers, a finger carried thereby and guided by said rods for engaging said extension to close said stanchion, and a latch member hingedly mounted on one of said rods adapted to swing across the path of said extension to lock it in closed position regardless of the position of said fingers.

5. In a stall front, a top bar comprising spaced longitudinal U-shaped members, means for supporting said members in spaced
15 relation comprising a member spacing said first-named members apart laterally, clamping
ingly embracing the latter and containing a guide, and a rod slidable in said guide.

6. In a stall front, a top bar comprising spaced longitudinal U-shaped members, means for supporting said members in spaced
20 relation comprising upper and lower members embracing said first-named members and spacing the latter apart and laterally clamping
them, one of said second-named members containing a guide, and a rod slidable in said guide.

7. In a stall front, a top bar comprising spaced longitudinal U-shaped members,
30 means for supporting said members in spaced relation comprising upper and lower members embracing said first-named members and spacing the latter apart and laterally clamping
them, one of said second-named members containing a guide and a vertical bolt clamping
said second-named members in position.

8. In a stall front, a top bar comprising spaced longitudinal members, a stanchion pivotally hung beneath said bar and having a
40 side bar pivotally mounted at its front end, said side bar being guided by said top bar, a spacer member on said bar above said stanchion, means controlling the position of said side bar and comprising a slidably
45 mounted rod, and a latch for said side bar rotatably mounted on said rod, and means on said spacer member interlocking with said latch to prevent movement of said latch along said rod.

50 9. In a stall front, a top bar comprising spaced longitudinal members, a stanchion pivotally hung beneath said bar and having a side bar pivotally mounted at its front end, said side bar being guided by said top bar, a spacer member on said bar above said stanchion to which said stanchion is pivoted at its upper end, means controlling the position of said side bar and comprising a slidably
55 mounted rod, and a latch for said side bar rotatably mounted on said rod, and means on said spacer member interlocking with said latch to prevent movement of said latch along said rod.

10. A stall front having a supporting structure, a plurality of stanchions supported by

said structure to swing in a substantially horizontal plane, each of said stanchions having a side bar pivotally mounted at its lower end to swing laterally, each of said side bars having a part guided by said supporting structure and adapting said side bars to swing at their lower pivotal mountings, and means for controlling the swinging of said side bars comprising a sliding member, means on said member for operating said side bar, a lever for operating said sliding member, said lever being pivotally mounted on a vertical corner post of the stall and having a link connecting it to said sliding member, said link being movable to either side of said post to permit the lever to be reversed.

11. A stall front having a supporting structure, a plurality of stanchions supported by said structure to swing in a substantially horizontal plane, each of said stanchions having a side bar pivotally mounted at its lower end to swing laterally, each of said side bars having a part guided by said supporting structure and adapting said side bars to swing at their lower pivotal mountings, means controlling the swinging of said side bars and cooperating with said parts and comprising a member slidable along said supporting structure and latch members cooperating with said parts and journalled on said member and interlocked with said supporting structure to prevent longitudinal movement, said latch means being movable selectively at their journal support on said member into a position to retain the ones of said side bars with which they cooperate in closed position while the remainder of said side bars are rendered free to move under the control of said first-named means.
